UNITED STATES PATENT OFFICE.

DARIUS FERRY, JR., OF BROOKLYN, NEW YORK.

DESIGN FOR A TOBACCO-BAG.

SPECIFICATION forming part of Design No. 22,674, dated August 8, 1893.

Application filed February 24, 1893. Serial No. 463,631. Term of patent 7 years.

To all whom it may concern:

Be it known that I, DARIUS FERRY, Jr., a citizen of the United States, and a resident of Brooklyn, in the county of Kings and State of New York, have invented and produced a certain new and original Design for Tobacco-Bags, of which the following is a specification.

Reference being had to the accompanying drawings, illustrating my new and original design, and in the figures of which like parts are designated by similar letters of reference, Figure 1, is a top view of the package; and Fig. 2, is a transverse sectional view.

The body *a*, of the package may be of any material suitable for the purpose, the top having an opening which is closed by the drawing strings *b*, *b'*. When the package is filled,

the filling distends the same, causing said package to assume the shape or contour illustrated in the accompanying drawings, namely, ²⁰ elliptical in plan view, and also elliptical in cross sections taken on the major and minor axes.

What I claim as new, and desire to secure by Letters Patent, is—²⁵

The design for tobacco bags, substantially as herein shown and described.

Signed at New York, in the county and State of New York, this 20th day of February, A. D. 1893.

DARIUS FERRY, JR.
